MANICURING INSTRUMENT

Margaret Alice Mary Molyneux-Seel, London, and
Tomaso Bruno Bertuccioli, Fornborough, Eng-
land

Application July 20, 1933, Serial No. 681,376
In Great Britain July 23, 1932

7 Claims. (Cl. 132—73)

This invention relates to improvements in manicuring instruments, and has for its chief object to provide an improved cuticle remover. In using cuticle removers, as heretofore constructed, it has been necessary periodically to dip the instrument into the solution being used. This disadvantage is overcome by means of the present invention according to which the cuticle remover is provided with a reservoir for the solution in question, the supply of the solution to the end of the device being controlled by means of a suitable valve.

The valve may be of any suitable form, but is preferably spring-controlled and adapted to be operated by a finger operated plunger which is adapted to open the valve and allow the fluid to flow drop by drop.

The instrument has been illustrated by way of example in the appended drawing wherein Fig. 1 is a view of one form of the instrument, Fig. 2 is a section and Fig. 3 is a section showing operation of the same; Fig. 4 is a sectional view of a modification.

The device comprises a tube or barrel of metal 1, the material sold under the registered trademark Bakelite, or any other suitable material. The lower end of this tube, which is intended to receive the solution, is of reduced diameter and is screw-threaded externally to receive a removable tip 2 which may be made of the same or a different material to the tube itself, this tip being shaped, if desired, to the usual form of a cuticle remover, i. e. flattened on the underside and slightly curved at its end. The tip is provided with a central bore 3 having an orifice, say, one quarter of an inch in diameter. The upper end of the tube is screw-threaded to receive a cap 4 which screws into the tube and is provided with a central bore 5, in the upper end of which is located a button or plunger 6, the edge of the bore being spun over as shown in 7, or otherwise arranged, to form a stop against which a flange 8 on the plunger 6 abuts to limit the outward movement of the plunger. Attached to the underside 45 of the plunger is a rod 9 which passes through a hole 10' in a suitable washer or disc 10 in the cap which thus forms a bearing for the rod. A compression spring 11 is disposed between this disc and the plunger to return the plunger to its outer position, and the inward movement of the plunger 6 may be limited for a purpose herein-after explained either by reason of the coils of the compression spring 11 abutting against one another or by reason of the amount by which 55 the plunger projects beyond the cap, the finger

in the latter case coming up against the cap to prevent further inward movement of the plunger (as shown in Fig. 3).

The hole 10' through which the plunger rod slides is preferably a good fit around the plunger rod so as to prevent the solution in the tube leaking past the same while allowing air to pass.

Suitably disposed within the tube is a further web or disc 12, preferably provided with recesses 13 around its edge to allow a free flow of solution past this web. This web forms a bearing for the valve spindle 14, which, at its upper end, is provided with a head 15 against which the lower end of the plunger rod 9 bears. The valve proper comprises a conical member 16 on the lower end of the valve spindle which co-operates with a conical seating in a web 17 across the lower end of the tube, the conical surfaces being so disposed that the valve spindle has to be pressed down to open the valve. The valve 75 proper is extended on its further side also as a long cone 18 which is located in the bore in the tip 2 and may be arranged to close the exit orifice when the valve is open, if desired.

A compression spring 19 is arranged between 80 the web in the tube and the head on the valve spindle to keep the valve normally closed.

To fill the device, the cap is removed and the solution poured in, the valve during this operation being kept closed. The cap is then screwed 85 on again, and when it is desired to use the device, the plunger is depressed by the finger to allow a small quantity of the solution to flow into the tip from whence it passes to the finger nail. As soon as the pressure is released, the valve will 90 close, and it will be seen that by limiting the inward movement of the plunger, as above described, it can be ensured that the valve will not open too far.

Many modifications may be made in the above 95 described constructional form of this invention. Thus, for example, in the modification of Fig. 4 the tip 2' is screwed on to the lower end of the tube and is bored out to receive a thin tube 20 which projects from the lower end of the tube 100 1'. The bore 3' in the tip communicates with the edge of the tip by means of a fine passage 21. The supply of the solution from the barrel to the tip is controlled by a needle 22 which projects down the centre of the solution receiving tube 105 and also the fine tube. This needle is carried by a cap 23 which screws on to the upper end of the tube, the needle being secured to a small spring-controlled plunger 24 carried by the cap 23 so that by depressing the plunger with the finger 110

the needle may be made to move up and down in the thin tube. A compression spring 25 is arranged between the plunger and a shoulder 26 in the cap and a rubber washer 27 is arranged on the underside of the shoulder to render the joint between the tube and the cap air-tight. With the cuticle remover, according to the present invention, it is merely necessary to depress the plunger knob to cause a drop of solution to flow down the bore in the tip on to the nail, after which the cuticle remover is used in the usual manner. This device may be filled by unscrewing the cap 23 partly only and introducing the solution by a hole 28 in the threaded portion of the barrel.

It will thus be readily appreciated that the cuticle removers, according to the present invention, will be very simple and easy to use and will furthermore obviate the necessity of frequently dipping the cuticle remover in the solution.

In a further modification, the thin tube 20 above referred to may be provided with fine holes 29 to facilitate the flow of the solution. Again, any other form of valve, which will allow the solution to be fed drop by drop to the tip, may be employed.

Having now fully described our said invention, what we claim and desire to secure by Letters Patent, is:

1. An improved cuticle remover comprising a hollow body portion, a removable tip portion provided with an axial bore flared inwardly, a valve seating in said body portion for a valve having a spindle extending through said body portion and operated by a spring to apply said valve in said seating externally to said body portion, a removable cap mounted on the end of said body portion opposed to said tip and containing a pressure button adapted to operate the spindle of the valve to open said valve, said valve being provided with a conical projection extending in said conical bore to close the orifice of the bore when the valve is open.
2. An improved cuticle remover comprising a hollow body portion, a removable tip portion provided with an axial bore flared inwardly, a valve seating in said body portion for a valve having a spindle extending through said body portion and operated by a spring to apply said valve in said seating externally to said body portion, a removable cap mounted on the end of said body portion opposed to said tip, a spring urged push-button protruding from said cap, means limiting the movement of said push-button outside said cap, said push-button having a guide spindle contacting with the end of the valve spindle whereby pressure on the button will open the said valve, means for providing liquid-tight closure around said push-button and spindle, and means whereby operation of the valve will close the orifice of the bore in the tip portion.

3. An improved cuticle remover comprising a hollow body portion, a screwed tip portion provided with a central bore, and a screwed top portion, said body portion comprising a thin tubular extension provided with lateral holes and extending into said central bore, a needle extending in said tubular extension and formed as an extension of a finger button disposed within said top portion and spring urged outside said top portion, means limiting the movement of said button in both directions, and means for providing a fluid-tight joint around the spindle in the top in the movements of said spindle.

4. An improved cuticle remover comprising a hollow body portion, a screwed tip portion provided with a central bore, and a screwed top portion, said body portion comprising a thin tubular extension provided with lateral holes and extending into said central bore, a needle extending in said tubular extension and formed as an extension of a finger button disposed within said top portion and spring urged outside said top portion, means limiting the movement of said button in both directions, a hole in the threaded portion of the body for filling the instrument by partly unscrewing the top, and means for providing a fluid-tight joint around the spindle in the top in the movements of said spindle.

5. An improved cuticle remover comprising a reservoir which communicates at one end with a hollow tip provided with a discharge orifice, a feeder located within the reservoir and movable longitudinally thereof for feeding liquid to the discharge orifice, said feeder having a pointed extension in the hollow tip closing the said discharge orifice when the feeder is operated, and operating means for the feeder disposed at the other end of the reservoir.

6. A manicuring instrument comprising a reservoir which communicates at one end with a hollow tip conformed externally to remove the cuticles and provided near its outer end with a discharge orifice, a needle which reaches through a bore of slightly greater diameter than the needle in the end of the reservoir connected to the tip and which is arranged with its pointed end directed toward the discharge orifice, and operating means for the feeder disposed at the other end of the reservoir.

7. An improved cuticle remover comprising a hollow body portion forming reservoir which communicates at one end with a hollow tip provided with a discharge orifice, a spring-controlled feeder located within the reservoir and movable longitudinally thereof for feeding liquid to the discharge orifice, said feeder having a pointed extension in the hollow tip closing the said discharge orifice when the feeder is operated, and a finger operable plunger for operating the feeder from the other end of the reservoir.
